CONVERTIBLE BASSINET AND CHILD'S SEAT

Hyman Mover, Marblehead, Mass., assignor to
 Bunny Bear, Inc., Everett, Mass., a corporation
 of Massachusetts

Application February 19, 1947, Serial No. 729,435.

6 Claims. (Cl. 5—98)

1

The present invention relates to a convertible bassinet and child's chair particularly adapted to use in carrying infants and children in automobiles.

An object of the invention is to provide an accessory of the character indicated which is of simple construction and therefore readily manufactured, but which, nevertheless, is comfortable and reliable in use.

Another object of the invention is the provision of a convertible bassinet and seat which may be quickly and conveniently converted from a bassinet suitable for the use of infants to a seat or chair suitable for the use of small children.

An illustrative embodiment of the invention is shown in the accompanying drawings, wherein:

Fig. 1 is a perspective view of the accessory in condition for use as a bassinet;

Fig. 2 is a perspective view of the accessory converted for use as a seat or chair;

Fig. 3 is a horizontal section on line 3—3 of Fig. 1;

Fig. 4 is a detail of the joint in the leg braces; and

Fig. 5 is a detail of a part of the main frame.

Referring to the drawings, the convertible bassinet and seat of the present invention comprises an open, generally rectangular, main frame of metal rod or strip stock to which a textile hammock member 2 is secured by a hem formed around the edge of the hammock member. The textile hammock member is of sufficient fullness to form a pocket or sack, as shown. The main frame is extensible in length in a manner to be described in greater detail hereinafter.

The main frame is formed by a pair of U-shaped frame sections indicated generally at 3 and 4. The frame sections 3 and 4 have their free ends connected together by joints 5 and 6, shown in detail in Fig. 5. Referring to Fig. 5, each joint comprises a clip 7, U-shaped in cross-section, which is secured to the frame section 3 by a rivet 8 and supports the frame section 4 by means of a rivet or pin 9. It will be observed that the connection between the frame sections 3 and 4 is such that they cannot be moved upwardly with respect to each other from the position shown in Fig. 1 but that either frame section may be swung downwardly about the pin 9 with respect to the other frame section. The textile hammock member 2 may be cut away as indicated at 10 and 12 to expose the joints and the adjacent parts of the frame sections.

Legs are provided for supporting the main frame above the floor or car seat a distance sufficient to

2

keep the bottom of the cloth hammock free of the floor or seat. These legs are formed by U-shaped metal members 14 and 16 having their free ends pivotally connected to the main frame sections 4 and 3 respectively by rivets 18 and 20 or other suitable fasteners. The legs may be swung about their pivots into a vertical position, in which they support the bassinet in spaced relation to the floor or seat of the car, or into a horizontal position to permit the device to be conveniently carried or stored.

The leg 14 is provided on each side with a folding brace 22 connected at its lower end to the leg 14 by rivet 24 and connected at its upper end to 15 the side of the main frame section 4 by a rivet 26 at a point spaced from the rivet 18. The braces 22 are jointed at 28 to permit them to be folded to permit inward and upward movement of leg 14 and are provided with stops 30 (Fig. 4) and with 20 projections 32 and depressions 33, struck out of the metal of the braces 22, to limit movement of the parts of the brace 22 about the joint 28 to a single direction.

The leg 16 is provided with similar braces 34 and 36 which may be folded in the same manner as the braces 22.

The forward end of the frame member 4 is adapted for movement with respect to the remainder of the frame 4. As shown, the forward 30 end of the frame is formed by a separate U-shaped member 38 whose legs 40 extend rearwardly and are provided with slots 42 for the reception of the rivets 18 of the leg 14. Additional rivets 44 lying entirely beneath the hem of the 35 textile member 2 are passed through the slots 42 to prevent swinging movement of the extensible end member 38 with respect to the remainder of the frame 4. The slots 42 are of a size to permit free sliding movement of rivets 18 and 44 therein. The member 38 is shown in Fig. 1 in partly 40 extended position, from which position it may be moved inwardly or outwardly.

The textile hammock member 2 is provided with a strap 46 and a correspondingly positioned strap 48 having on its free end a buckle 50 for the reception of the free end of the strap 46. These straps 46 and 48 may be joined together over an infant in the hammock 2 to hold the infant safely in position during travel of the car.

To convert the bassinet to the seat or chair of Fig. 2, the two main frame sections 3 and 4 are adjusted into positions approximately at right angles to each other as shown in Fig. 2 by movement of the sections about the joints 5 and 6. 55 This movement brings the leg 14 rearwardly so

that its lower crosspiece 15 is positioned adjacent the corresponding crosspiece 17 of the leg 16. The crosspiece 17 is provided with a latch comprising a metal clip 56 secured to its upper surface by rivets 58 and 60 and carrying a pair of upwardly extending spring arms 62. To latch the crosspiece 15 in position adjacent the crosspiece 17, and secure the main frame in its converted condition, the crosspiece 15 is first drawn upwardly sufficiently to clear the upper ends of the spring fingers 62, with some springing of the metal parts comprising the frame and the legs 14 and 16, and is then dropped downwardly between the spring fingers 62. When the accessory is converted for use as a seat, the extensible part 38 of the frame section 4 will ordinarily be moved to its inwardmost position.

The rear transverse member of the frame member 3 carries a pair of hooks 64 and 66 for engagement with the back of an automobile seat. These hooks are pivoted in clips 68 and 70 respectively, which clips are pivoted on the frame member 3. This pivotal connection may be made by means of rivets 72 and 74 or by means, such as a bolt and wing nut, permitting the hooks to be detached.

A detachable bail 76, formed of wire, has its outwardly turned ends 78 and 80 hooked into apertures provided in the vertical members of the legs 16.

For use with the device when converted into its seat form, a removable stretcher 82 is provided adjacent the joints 5 and 6 in the main frame as shown. The stretcher 82 is provided at one end with an upwardly turned end 84. At its other end it is formed with an upwardly turned portion 86 merging into a horizontal portion 88 to which is connected a depending portion 90. The free ends of the portions 90 and 84 are swaged or riveted over, as shown at 85 in Fig. 6, so that they are of a slightly larger diameter than the major portion of the end portions 90 and 84 of the stretcher 82.

The stretcher 82 is held in position between the side members of the main frame by means of a pair of identical clips 92 and 94 secured to frame section 3 so as to provide an aperture for the reception of the ends of the stretcher. The clip 92, as shown in Fig. 5, comprises a curved central section 96 and end portions 98 and 99 disposed in a common plane and secured to the frame member 3 by the rivet 8 and a rivet 102. The central section 96 is spaced from the side member 3 just sufficiently to permit the enlarged upper end of the portion 84 to be forced into the space between the clip and the side member of the frame. The clip 94 serves in the same manner to secure the downwardly turned portion 90, at the other end of the stretcher 82.

A strap 110 is stitched to the hammock member 2 adjacent the forward edge of the seat portion of the chair and is adapted to be passed upwardly over the stretcher 82 and then downwardly and to have its free end secured in the buckle 112.

Referring to Fig. 1, a strap for further assisting in holding the child in the chair is attached to the textile member 2 and comprises a strap member 104 and a similar member 106 carrying a buckle 108 on its free end.

Metal arm members 114 and 116 may be provided on the inner surfaces of the side members of the frame member 3.

For carrying small infants in the automobile the accessory is converted to its bassinet form,

shown in Fig. 1. The bassinet may be placed on the floor of the car but preferably is placed with the legs 14 resting on the rear seat and the hooks hooked over the top of the back of the front seat to support the end of the accessory which carries the legs 16. When the accessory is in this form, the stretcher 82 need not be employed and the bail 76 ordinarily will be removed. The infant is placed in the hammock member 2. The straps 104 and 106 may be drawn over the infant and joined together by the buckle 50. A mattress or pad may be placed in the bottom of the hammock 2 if desired. The hammock 2 may sway to a limited extent in keeping with the motion of the car, and the infant is safely supported so that there is no danger that he will be thrown or bounced against any hard metal parts of the car or of the accessory under any ordinary riding conditions. The accessory in the form shown in Fig. 1 may be used generally as a bassinet, in addition to its use with an automobile.

If the accessory is to be used for a child large enough to sit up alone, it is converted to the form shown in Fig. 2 and may then be used as a seat or chair for general use. It may be placed on the floor or the seat of the car when the child is to be carried in the car. The bail 76 may be hooked into the slot between the seat back and the cushion to secure the seat in place in the car. The child may be strapped in the seat by use of the straps 104 and 106, and the strap 110 may be passed about the stretcher 82 to further protect the child from sliding forwardly out of the seat.

The accessory may be folded flat for shipment or storage by folding the frame sections 3 and 4 into the relative positions shown in Fig. 1 and then folding the legs 14 and 16 inwardly and upwardly. The hooks 64 and 66 are folded into the general plane of the main frame by suitable adjustment of the clips 68 and 70 on the frame section 3 and of the hooks 64 and 66 within the clips 68 and 70.

I claim:

1. A convertible bassinet and child's chair comprising an extensible, open, sectional frame including two U-shaped members hinged at their open ends and turned in towards one another in a common horizontal plane, said hinges comprising, joints connecting one section of the frame to the other section of the frame for movement of the frame sections downwardly only from the position in which they lie in said common horizontal plane, one of said U-shaped members having extensible side portions on both sides near the closed end of the U whereby the U may be extended in said common horizontal plane a hammock member connected at its edges to said frame and suspended therefrom, and legs for supporting said frame connected thereto in the fixed and not extensible part of the frame.

2. A convertible bassinet and child's chair comprising an open sectional frame including two U-shaped members hinged at their open ends and turned in towards one another in a common horizontal plane, said hinges comprising, joints connecting one frame section to the other frame section for movement of the frame sections downwardly only from the relative position in which they lie in said common horizontal plane, one of said U-shaped members having extensible side portions on both sides near the closed end of the U whereby the U may be extended in said common horizontal plane a textile hammock member connected at its edges to said frame and suspended therefrom, one of said frame sections hav-

ing means providing an aperture adjacent each joint, and a stretcher connecting the sides of said frame section and having its ends positioned in said apertures.

3. A convertible bassinet and child's chair suitable for use in an automobile comprising an open sectional frame, joints connecting one frame section to the other frame section for movement of the frame sections downwardly only from the relative position in which they lie in a common horizontal plane, a hammock member connected at its edges to said frame and suspended therefrom, a U-shaped leg on each frame section having its free ends connected to the section adjacent the outer end thereof, said legs and frame sections being so shaped and proportioned that the lower portions of said legs are positioned adjacent each other when said frame sections are moved about said joints into positions approximately at right angles to each other, and a latch on one leg for detachably connecting said legs.

4. A convertible bassinet and child's chair comprising an open frame formed by a pair of U-shaped frame sections, one of said sections being extensible in length, a pair of joints each connecting a free end of one frame section to a free end of the other frame section for movement of the frame sections downwardly from the relative position in which they lie in a common horizontal plane, a hammock member connected at its edges to said frame and suspended therefrom, a U-shaped leg on each frame section having its free ends connected to the section adjacent the outer end thereof, said legs and frame sections being so shaped and proportioned that the lower portions of said legs are positioned adjacent each other when said frame sections are moved about said joints into positions approximately at right angles to each other, and a latch on one leg for detachably connecting said legs.

5. A convertible bassinet and child's chair comprising an open frame formed by a pair of U-shaped frame sections, means for extending one of said frame sections in length in the plane of said frame section, a pair of joints each connecting a free end of one frame section to a free end of the other frame section for movement of the frame sections downwardly only from the relative

position in which they lie in a common horizontal plane, a textile hammock member connected at its edges to said frame and suspended therefrom, one of said frame sections having means providing an aperture adjacent each joint, and a stretcher connecting the sides of said frame section and having its ends positioned in said apertures.

5 6. A convertible bassinet and child's chair suitable for use in an automobile comprising an open frame formed by a pair of U-shaped frame sections, one of said sections being extensible in length, a pair of joints each connecting a free end of one frame section to a free end of the other frame section for movement of the frame sections downwardly only from the relative position in which they lie in a common horizontal plane, one of said frame sections having an aperture adjacent each joint, and a stretcher connecting the sides of said frame section and having its ends positioned in said apertures, a hammock member connected at its edges to said frame and suspended therefrom, a U-shaped leg on each frame section having its free ends connected to the section adjacent the outer end thereof, said legs and frame sections being so shaped and proportioned that the lower portions of said legs are positioned adjacent each other when said frame sections are moved about said joints into positions approximately at right angles to each other, and a latch on one leg for detachably connecting said legs.
